REFRIGERATOR LATCH

Lloyd L. Anderson, Grand Rapids, Mich., assignor
to Winters & Crampton Corporation, Grand-
ville, Mich., a corporation of Michigan

Application June 15, 1938, Serial No. 213,811

10 Claims. (Cl. 292—63)

This invention relates to latches which, in the embodiments disclosed, are particularly adapted for use on refrigerators. The latches of this invention are not limited necessarily to refrigerator use but are available in many places where a door is to be releasably latched in closed position.

It is an object and purpose of the present invention to provide a very useful, practical and serviceable latch which is very simply constructed and has few parts and is, therefore, economical to produce. At the same time the latch is sure and positive in its action, holding the door securely in closed position and being very quickly and easily released, with a minimum of movement of the manually operable releasing means used for such purpose.

An understanding of the invention may be had from the following description, taken in connection with the accompanying drawings, in which:

Fig. 1 is a fragmentary section of a refrigerator door and adjacent portion of the refrigerator casing, the latch being shown in elevation and engaged with a keeper on the casing.

Fig. 2 is a section through the refrigerator door substantially on the line 2—2 of Fig. 1, looking in the direction indicated by the arrows.

Fig. 3 is a longitudinal section through the immediate latch structure and between the opposite sides thereof, showing the position of the latch bolt when it is in operative closed position; also when the door is fully open.

Fig. 4 is a section showing the latch bolt and the retaining means therefor in releasing position as when the door is being opened.

Fig. 5 is an underplan view of the interior latch mechanism, a section being taken through the support immediately inside the connecting web between the opposite sides of the support.

Fig. 6 is a view somewhat similar to Fig. 1, showing the same invention in a slightly different form of latch structure and with a different form of operating or releasing means therefor.

Fig. 7 is a fragmentary section of the handle operating means for releasing the latch, the section being taken substantially at right angles to the plane of Fig. 6, and

Fig. 8 is a like section, somewhat enlarged, showing the position of the parts upon full release of the latch, Fig. 7 showing such position when the latch is in operative door closing position, and after the door is fully opened and the handle released.

Like reference characters refer to like parts in the different views of the drawings.

The door 1 of a refrigerator, at its free vertical edge portion, overlaps the adjacent front edge of a side of the refrigerator casing 2. The latch is preferably mounted on the door and a keeper for the latch bolt at the inner side and adjacent the free forward edge of said side of the casing. Such keeper is illustrated at 3 as having a bolt receiving recess 4 and an inclined flange 5 over which the bolt rides to be retracted until it comes to said recess 4 in the operation of shutting the door.

The door 1, adjacent its free vertical edge and at its inner portion has a recess at 6 in which the latch is mounted. The latch includes a sheet metal support substantially of U-shape having a web 7, and parallel spaced apart sides 8 extending outwardly at right angles to the web, the sides being provided with outturned flanges 9 through which screws or other fastenings may pass to secure the latch to the door. The sides 8 are provided with arc-shaped slots 10, as shown, toward the ends thereof farthest away from the edge of the door, and curving from what may be termed their inner ends outwardly toward said farther ends of the sides 8, as shown in Figs. 1 and 3.

A pin 11 extends transversely between the sides 8 and at its ends is received in the two slots 10. The latch bolt of the latch includes two spaced apart flat bars 12 which are longitudinally slotted adjacent their inner end portions at 13, the pin 11 passing through said slots. Said bars between their outer ends carry a latch dog or head 14 which is adapted to enter the recess 4 of the keeper. The dog has a substantially flat outer face 14a (Fig. 3) to bear against an adjacent flat side of the keeper recess 4, and also has a curved or cam surface 14b at its inner side to ride against the incline 5 of the keeper, previously described, when the door is closed. A flat metal member 15 is mounted at one end on the pin 11 and extends toward the latching dog 14, and said dog has a projection 16 extending toward the member 15, a coiled compression spring 17 having its end portions located over the parts 15 and 16 (Fig. 3). The spring 17 is a compression spring which tends to project the latch dog outward and move the bars 12 connected thereto outward until stopped by the engagement of the pin 11 with the inner ends of the slots 13. The dog 14 lies between the web 7 and a roller 18 mounted on a cross pin 19 between the sides 8. 55 When the dog is in its latching position (Figs. 1

and 3) the bars 12 lie substantially parallel to the web 7 and the pin 11 is at the end of the slot 10 nearest said web. When the latch is in releasing position (Fig. 4) the pin 11 has traversed the slot 10 to the opposite end away from the web 7, and the bolt is disposed at an acute angle to said web 7, the dog 14 being drawn inwardly from its outer position in Fig. 3 to that shown in Fig. 4.

A U-shaped abutment holding member of sheet metal is provided comprising a cross member 20 and two parallel arms extending therefrom, the arms being pivotally mounted between their ends on a cross pin 22 which lies between the sides 8 a distance outward from the pin 11 when the latch bolt is in its operative latching position (Fig. 3). A coiled spring 23 around the pin 22 has one end engaged with the cross member 20 and the other connected with a side 8 of the support, the tendency of which is to turn the arms 21 in a clockwise direction so as to bring the notched or recessed ends 24 of said arms 21 in the path of movement of the pin 11, providing a stop to hold said pin against movement along the slots 10. The notch or recess at 24 in each end of each arm 21 is so shaped that any force applied against the side 14a of the dog 14 tending to move the latch bolt to the position shown in Fig. 4 is transmitted through the pin 11 in a direction or line of force passing through the axis of the pin 22. Thus the U-shaped member consisting of the cross member 20 and the arms 21 provides a positive lock against retraction of the latching bolt due to a tilting or a partial swing action thereof until said lock has been moved counterclockwise about the pin 22 to release the pin 10, whereupon the bolt may retract and turn to its annular position, shown in Fig. 4, the pin riding against the edges 25 of the arms 21 and swinging the holding member further in a counterclockwise direction after such holding member has first been manually moved a sufficient distance to release the pin.

In the construction and installation illustrated in Figs. 1 and 2, the operating means for moving this latch bolt holding member includes a handle 26 secured at the outer side of the door, having a web 26a extending to the face of the door, said web being recessed, and with a pin 27, the inner end of which bears against the cross member 20, extending therefrom through the face of the door 1 and into said recess of the web 26a. Said pin adjacent its outer end is provided with an annular flange 27a. A coiled compression spring 28 is located around the pin within said recess of the web between the flange and the face of the door, the normal effect of which is to move the pin outwardly. A push bar 29 has its outer portion extending through a longitudinal slot in the handle 26 and engages the outer end of the pin 27. It is evident that on pushing inward on the bar 29 a short distance spring 28 will be compressed, and the arms 21 of the latch bolt holding member swung sufficiently to one side to release the pin at 11, permitting the bolt, upon the door being opened, to turn from the position shown in Figs. 1 and 3, to the releasing position shown in Fig. 4 and thus release the door for opening.

In Figs. 6 to 8, the latch structure is the same but the holding member serving as an abutment to hold the latch in operative position is transferred to and mounted upon the releasing handle pivot pin. The bolt comprising the latch dog 14 and the bars 12, the support comprising

the web 10 and the sides 80, and the roller 18, the pin 11 and the slot 10 which the pin traverses are the same. The sides 80 of the support are continued outwardly at their inner ends substantially at right angles, as at 81, joined at their outer ends by cross portion 82 from which ears 83 extend outwardly on which, as later described, the handle is mounted. The abutment holding member comprised of the parts 21 and 22 is not used. A sheet metal stirrup 30 is connected with the pin 11 and has connected thereto a rod 31 which lies between the sides 81, passes through the part 82 and also through a plate 32, forming the base of a handle housing 33 and over which said housing is releasably snapped, said base being fastened by screws or other suitable connections, as in Fig. 6, to the door 1.

A pin 34 is carried by and between the sides 83 on which a sheet metal handle 35 is pivotally mounted. A second pin 36 is carried by and between the sides 83 spaced from the pin 34, the sides of the handle having slots 37 through which the pin passes, serving to limit the outward distance that the handle may be moved, as shown in Fig. 8. A coiled spring 38 is wound around the middle portion of the pin 34 and has one end portion 39 thereof hooked over the pin 36. The other projecting end portion of said coiled spring engages against a holding dog made of a single piece of sheet metal having two spaced apart sides 40, connected integrally by an irregularly shaped sheet metal form which includes an annular flange 41, a rounded intermediate portion 42, and a terminal abutment lip 43, against which the upper end of the rod 31 engages when the door is closed. This holding or abutment member, influenced by the spring 38, is normally swung in a clockwise direction to the position shown in Fig. 7, bringing the flange 41 against the end 44 of the handle 35.

It is apparent that on grasping the handle and moving its free end outwardly from the position shown in Fig. 7 to that in Fig. 8, the lip 43 will be carried over and past the end of the rod 31, whereupon the rod moving outwardly as the door is opened, will engage against such abutment member and swing it still further or to the position shown in Fig. 8, if such position needs to be reached to permit the nose of the latching dog 14 to pass by the keeper. In moving to the position shown in Fig. 8, the spring 38 has its tension increased. The handle is normally acted upon by coiled springs 45 wound around the pin 34 at the outside of each side 40 of the abutment member, having one end 45a of each of said springs engaging with the handle at the shoulder 44 and the other engaging against the base 32 (Fig. 8). After the door is opened the tendency of the springs 45 and 39 is to return the handle and the holding abutment to the initial positions shown in Fig. 7, and thus swing the latch bolt back from the position which it has taken, as in Fig. 4 when the door is being opened to the position in Fig. 3, whereupon the bolt is again held against its tilting and retracting movement.

The latch bolt being in the position shown in Fig. 3 or in a position like that shown in Fig. 6 (with the other form of latch) when the door is open, on closing the door spring 17 is compressed and the cam side 14b of the bolt head 14 rides over the incline 5 of the keeper until the recess 4 of the keeper is reached, whereupon spring 17 projects the bolt head into said recess. The doors are equipped with compressible gaskets 46 for the exclusion of warm air from the outside

or the escape of cold air from the inside of the refrigerator. These gaskets are compressed upon the door being fully closed and power is stored in them, causing them to tend to move the door partly opened as soon as the pin 11 is released. With either form of latch, as soon as the pin 11 is free to traverse the slots 10, the pressure exerted by the gaskets at 46 will cause the door to swing outwardly, and as the door moves outwardly the bolt is turned more and more from the position shown in Fig. 3 eventually to the position in Fig. 4, in which position the head 14 disengages entirely from the keeper and the door may be fully opened. And then as previously outlined, on release of the latch operating means, either the push bar 29 or the handle 35, depending on which form of releasing means is used, the latch bolt returns to its original position and is held in such position.

The structure described is strong and durable and fully capable of withstanding the service to which it is subjected in use. The door when latched is securely latched. Its release is exceptionally easy, there being required only a relatively small movement of the manually operated releasing member, the push bar 29 or the handle 35. For as soon as the pin 11 is released to move in slots 10, its movement along said slots with the accompanying tilting and retracting of the latch bolt is not caused by any further manual operation of either the push bar 29 or the handle 35, but is caused by the engagement of the bolt 14 with the keeper from which comes the following swinging and retraction of the latch bolt, as the door is moved to open position sufficient for the latch bolt to escape from the keeper.

The latch is of a simple and economical structure and may be produced at low cost. The invention is defined in the appended claims and is to be considered comprehensive of all forms of structure coming within their scope.

I claim:

1. In a latch structure, a support having spaced apart sides and a cross member connecting the sides at one edge thereof, the sides of said support having slots therein, a pin extending between the sides of the support having its ends received in said slots, a latch bolt connected with said pin and adapted to occupy a latching position substantially parallel with the cross member between the sides of the support, in which position one end of the bolt projects beyond the adjacent end of the support, said latch bolt being retractile on movement of the pin along said slots and tiltable when retracted to an acute angle with respect to said cross member of the support, releasable means for holding the pin at one end of said slots in which the latch bolt is in said first mentioned position and at one end projects beyond the support, and means for holding the projecting end portion of said latch bolt against movement away from said cross member of the support.

2. A latch structure comprising, a support of metal of channel form having spaced apart parallel sides and a web connecting said sides, said sides of the support having each an arc-shaped slot therein extending and curving away from said web, a pin extending between said sides of the support having its ends received in said slots, a latch bolt comprising a member connected with the pin, two spaced apart parallel bars having slotted end portions, the pin passing through said slots, a bolt head secured between

the outer ends of said bars and a coiled compression spring between said head and pin, said latch bolt in one position lying substantially parallel to the web and in such position having the head thereof extending beyond the adjacent end of the support, retaining means mounted on and extending between the sides of the support at the side of the head opposite that adjacent said web, and releasable holding means for said pin adapted to releasably hold the pin in a position wherein the bolt substantially parallels said web.

3. A latch structure comprising, a channel shaped support having spaced apart parallel sides connected by a web, a pin extending between the sides of the support, an arc-shaped guide on each side of the support to be traversed by the ends of the pin, a latch bolt connected with said pin and adapted to project at one end beyond the support and when thus projected lie substantially parallel to said web, and releasable holding means for holding the pin in the position in which said latch bolt projects at one end beyond the support, said holding means when released permitting the pin to traverse said guides and simultaneously retract and tilt said bolt.

4. A latch structure comprising, a support of metal of channel form having spaced apart parallel sides and a connecting web, a pin extending between the sides of the support, arc-shaped guides, one on each side of the support extending and curving away from said web, a pin located between the sides of the support having its ends associated with said guides whereby the pin may traverse the guides in moving toward or away from said web, a longitudinally extensible and retractile latch bolt connected to said pin adapted to lie substantially parallel to said web with one end of the bolt projecting beyond the support in one position, and be retracted and tilted on movement of the pin along said arc-shaped guides, and a pivotally mounted member located and pivotally mounted between the sides of the support having its free end adapted to engage said pin and hold it against movement and maintain said latch bolt in substantially parallel position to said web, said pivotally mounted member being adapted to be turned about its pivot to release said pin.

5. A latch structure comprising, a channel shaped support having spaced apart sides and a connecting web, an arc-shaped guide on each side of the support extending and curving away from said web, a pin between the sides of the support having its ends carried by said guides, a longitudinally expandible and contractile latch bolt connected at one end to said pin, a member pivotally mounted on and between the sides of the support, the pivotal axis thereof being a distance from said web, the free end of said member being adapted to interpose in the path of movement of said pin to hold it against traversing said arc-shaped guides, and yielding spring means for normally holding said member in operative position to stop said movement of the pin.

6. A latch structure comprising, a channel shaped support, arc-shaped guides, one on each side of the support, a pin extending between the sides of the support having its ends associated with said guides to traverse the same, a longitudinally extensible and retractile latch bolt connected to the pin and adapted in latching po-

sition to lie substantially parallel to and against the web of said support, a U-shaped abutment having spaced sides and a cross member connecting said sides at one end located between the sides of the support, a pivot pin mounted on said support passing through the sides of said holding abutment between the ends thereof, the free ends of said sides of the holding abutment being adapted to engage against said first mentioned pin and hold the latch bolt against retraction, and manually operable means to engage the cross member of said holding abutment to turn the same about its pivotal mounting and free said pin to traverse said guides.

7. A construction containing the elements in combination defined in claim 6, and retaining means mounted transversely between the sides of the support adjacent one end thereof, said latch bolt passing between said means and the web of said channel support.

8. A latch comprising a support, a latch bolt movably mounted on said support for inward and simultaneous tilting movement and vice versa, said latch bolt having a keeper engaging head housed within the support and adapted to project beyond one end of the support, said head upon the occurrence of said tilting and retracting movement moving inwardly with respect to the support and tilting away from said keeper with which it is engaged, and means for releasably holding the inner end of the latch bolt against movement.

9. In combination, a door, a latch mounted thereon comprising a channel shaped support, arc-shaped guides on the sides of the support extending and curving away from the web of

said channel support, a pin having its ends received in said guides, a longitudinally extensible and retractile latch bolt connected at one end to said pin and at its opposite end having a head adapted in one position to project beyond the support, the bolt in said position lying substantially parallel to the web of the support, an operating handle mounted on the door and means connected with said pin combined with movable means adapted to be operated by said handle for holding the pin and the connected latch bolt against movement but releasing said pin for movement along said guides on moving said handle.

10. In combination, a door, a latch mounted thereon comprising, a channel-shaped support having spaced apart sides and a web, arc-shaped guides on said sides extending and curving away from said web, a pin having its ends received in said guides, a longitudinally extensible and retractile latch bolt connected at one end to said pin, said bolt having a keeper engaging head at its opposite end adapted to project beyond the support in which position the bolt substantially parallels said web and said pin is at one end of said guides therefor, a rod attached to said pin extending outwardly to and beyond the outer side of the door, a handle pivotally mounted on said door, a pivotally mounted holding abutment engaging with the outer end of said rod and adapted to hold said bolt in said parallel position to the web, and interengaging means on said handle and holding abutment for releasing said abutment from said rod on manual operation of the handle.

LLOYD L. ANDERSON.
